US00D794595S

(12) **United States Design Patent** (10) **Patent No.:** **US D794,595 S**
(45) **Date of Patent:** **** Aug. 15, 2017**

(54) **ELECTRONIC DEVICE**

- (71) Applicant: **Samsung Electronics Co., Ltd.**, Suwon-si (KR)
- (72) Inventors: **Keemoon Lee**, Yongin-si (KR); **Kangmoon Kim**, Seoul (KR); **Junghyun Choi**, Seoul (KR); **Taejoong Kim**, Goyang-si (KR); **Junghyuck Im**, Yongin-si (KR)
- (73) Assignee: **Samsung Electronics Co., Ltd.**, Suwon-si (KR)
- (**) Term: **15 Years**
- (21) Appl. No.: **29/564,316**
- (22) Filed: **May 12, 2016**

(30) **Foreign Application Priority Data**

- Nov. 13, 2015 (KR) 30-2015-0057263
- (51) LOC (10) Cl. **14-03**

(57) **CLAIM**

We claim the ornamental design for an electronic device, as shown and described.

DESCRIPTION

FIG. 1 is a front perspective view of a first embodiment of an electronic device, showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is a front perspective view of a second embodiment of an electronic device, showing our new design;
FIG. 10 is a front view thereof;
FIG. 11 is a rear view thereof;
FIG. 12 is a left-side view thereof;
FIG. 13 is a right-side view thereof;
FIG. 14 is a top view thereof;
FIG. 15 is a bottom view thereof; and,
FIG. 16 is a rear perspective view thereof.

The broken lines in the figures show portions of the electronic device that form no part of the embodiment in which they are shown.

1 Claim, 12 Drawing Sheets
